UNITED STATES PATENT OFFICE.

BENJAMIN E. GETCHELL, OF PLAINVILLE, CONNECTICUT, ASSIGNOR TO THE TRUMBULL ELECTRIC MANUFACTURING COMPANY, OF PLAINVILLE, CONNECTICUT, A CORPORATION OF CONNECTICUT.

MULTIPLE-CIRCUIT SWITCH.

Application filed April 25, 1925. Serial No. 25,773.

My invention relates to switches for the control of a plurality of circuits and has for its main object to provide a switch in which two circuits are automatically opened in case of an overload in either one.

Another object is to provide a switch of this character which can be reset or restored without the trouble, hazard and expense of renewing fuses.

Another object is to provide a switch of this character which cannot be held closed against dangerous overload or short circuit.

Another object is to provide an overload switch of this character without requiring the use of magnetic coils of any description.

Another object is to provide a switch of this character in which there is a sufficient time lag to prevent unnecessary opening of the circuits on temporary non-dangerous overloads.

Another object is to provide a hand operable switch of this character in which the circuit may be automatically opened in case of an overload in either of two circuits.

The preferred form of mechanism which I have designed employs in each circuit a switch unit having a movable switch arm, an operating lever connected to the switch arm by a toggle device and a thermostatic element for operating the toggle device. The operating levers are connected by a manually operable device and the parts are so constructed and arranged that in case of an overload through either switch unit the thermostatic device opens the circuit of that switch unit and causes a throwing spring to move the parts so as to simultaneously open the circuit through the other switch unit.

I have shown the invention as applied to an enclosed type switch but it should be understood that the invention is not limited to such a construction and that it is not limited to the details herein shown and described.

Fig. 1 is a front view of a switch embodying improvements of an enclosed type switch of my invention, the cover being omitted.

Fig. 2 is a longitudinal sectional view

and side elevation of the same (with the cover in place) on the plane of the line 2-2 of Fig. 1.

Fig. 3 is a transverse sectional view on the plane of the line 3-3 of Fig. 1 looking upward.

Fig. 4 is a similar view showing a modified arrangement in which the switch units are located beneath the insulating base.

Fig. 5 is a longitudinal sectional view and side elevation on a larger scale showing one of the switch units in the open circuit position.

Fig. 6 is a similar view showing the switch unit in the closed circuit position.

Fig. 7 is a similar view showing the switch parts in the position they would occupy when the circuit has just been automatically opened.

Fig. 8 is a perspective view of the switch embodied in a casing, the cover being shown open.

Fig. 9 is a fragmentary perspective view showing the thermostatic element and connections.

In the form shown the switch elements are supported by an insulating base 10 and consist in this instance of two circuit breaking units 11 and 12. The operating crank 13 may be of any suitable character and provided with an external operating handle 14. While the invention is not limited to an enclosed switch I have shown a box having a body 15 with a hinged cover 16. This particular switch is intended for a three wire system in which the units 11 and 12 control the positive and negative circuits and the neutral line passes through the connecting strip 17.

Since the switch units are identical it will be necessary to illustrate and describe only one in detail. Each switch unit has a hinged or swinging contact member or arm 18 and a relatively stationary but yielding contact 19. The details of the preferred contacts are more fully shown and described and claimed in my co-pending application No. 20,611 filed April 4, 1925. In this particular form a contact arm 18 is pivotally supported by a post 20 which is secured to the base 10 by means of a screw 21. A spring 22 tends to move the switch

arm 18 to the open circuit position of Fig. 5.

The contact 19 is loosely secured to a bracket 23 which is secured to the base by a screw 24. The pin 25 which is secured to the contact 19 extends freely through a hole in the bracket 23 and has a spring 26 which holds the contact 19 yieldingly in place. In order to ensure a good electrical connection between the contact 19 and the terminal 27 I prefer to connect the contact to the terminal by means of a flexible conducting strip 28. In closing the switch to the position shown in Fig. 6 the tip of the contact arm 18 forces the contact 19 outwardly and the contact 19 is yieldingly pressed against the tip of the contact arm in a direction approximately radial.

The switch unit is provided with an insulating rocker 29 which is pivoted on the pin 30 in the post 31. The latter is secured to the base by a screw 32 which also holds in place the circuit terminal 33. This lever 29 has a slotted engagement with the operating crank 13. It is also connected to the switch arm 18 by means of a toggle member consisting of the links 34 and 35 which are hinged together.

A spring joint 36 tends to hold the lever 29 and the link 34 resiliently in the position shown in Fig. 5. The roller 37 at the hinged joint of the toggle member is adapted to roll along the abutment 38 when the crank 13 is moved manually to close the circuit. This abutment 38 takes up the thrust of the link 34 as the lever 29 is oscillated right handed as shown in Fig. 5.

The abutment member 38 is formed of thermostatic material adapted to bend or warp when heated by the passage of an overload current as shown in Fig. 7. This thermostatic member is of U-shape as shown in Fig. 9 and has one arm connected to the member 39 which is in electrical connection with the terminal 33 through the anchorage screw 32. The other arm of the U-shaped thermostatic member 38 is connected by means of the member 40 to the base of the main switch arm 18.

It will thus be seen that the parts are held in the open circuit position by the spring 22 as shown in Fig. 5 and also that the same spring 22 by virtue of the toggle like relation between the center of the lever 29 and the center of the arm 18 and the points of connection between the links 34 and 35 with said levers also holds the parts in the closed circuit position of Fig. 6. The switch may be opened by moving the operating crank 13 anti-clockwise in which event the spring 22 will move the switch arm 18 as soon as the joint 36 passes above the line of centers. The parts are also so designed that if the thermostatic element 38 is warped by the heating resistance developed by an

overload that the member 38 will lift the roller 37 into the position shown in Fig. 7 thus breaking the toggle at the middle point and allowing the spring 22 to act to open the circuit.

Thus far we have described a single switch unit as an independently operable structure and in many instances a switch may have any number of these units operating independently to protect various circuits without the need of any fuses. In some cases however it is desirable when one circuit is overloaded that two or more circuits should be opened substantially simultaneously. Such a condition may very readily be taken care of according to my invention by providing each rocker 29 with an extension or shoulder 41 adapted to be engaged by the link 34 when the circuit is thermostatically opened as shown in Fig. 7.

When the switch member 18 and spring 22 are thermostatically released the spring throws the links 34 and 35 so that the link 34 strikes against the shoulder 41, and forces the crank 13 counterclockwise as viewed in Fig. 7. This automatic movement of the lever 29 and crank 13 is transmitted to the corresponding levers of the other switch units which are connected to the crank 13. The action on the crank 13 is the same as the manual operation of the crank and accordingly opens all of the switch units automatically. In this automatic opening the tension of the spring joint 36 of the starting unit supplements the throwing spring 22 of the same unit so as to assist in overcoming the closing action of the spring joint of the switch which has not been opened by overload in its own circuit.

The spring 26 also assists in opening the circuit since the tip of the contact 19 presses against the edge of the tip of the arm 18 just as the circuit is being opened.

Preferably the switch units are mounted in channels in the insulating base so that insulating walls such as 42 and 43 are located at the sides of the switch units to protect them from each other and from the casing or other possible current carrying parts.

In the form shown in Fig. 4 the insulating base 10' is shown as supported by brackets 45 with the switch elements 11' and 12' underneath the base instead of on the outer surface as previously described. The operation of the crank 13' and the switch units however is the same in both cases.

In my co-pending application No. 20,931, filed April 6, 1925, I have more fully shown and described and claimed the individual switch unit.

I claim:

1. The combination of two switch units each having a thermostatic member and a spring for automatically opening its own circuit, a single crank for closing the cir-

cuit through both units and means whereby the automatic opening of one switch opens the other.

2. The combination of two switch units each comprising an operating lever, a switch contact arm, a toggle link connecting said arm and lever, a thermostatic member for moving said link, a spring for moving said arm, and means for moving said lever automatically when said link moves.

3. An operating crank, two levers connected thereto, two contact arms, toggle links connecting said arms and levers, a thermostatic member for opening the circuit through each arm and means of connection for releasing said crank and one lever and arm when the other arm is moved to an open circuit position.

4. A combination switch comprising a hinged switch member, a hinged manually operable member, a jointed toggle link connecting said members and a thermostatic

member for moving said link and releasing said switch member.

5. In an electric switch an operating lever, a hinged switch arm, a double jointed toggle connecting said lever and said arm and a spring for throwing said arm, a second spring co-acting between said toggle and said lever, said lever having a shoulder adapted to be engaged by said toggle and a thermostatic element for operating said toggle.

6. The combination of a plurality of switch units each having a thermostatic member and a spring for automatically opening its own circuit, a single crank for closing the circuit through all of said switch units and means whereby the automatic opening of the circuit by one of said switch units will open the circuit through the other switch units.

BENJAMIN E. GETCHELL.
